CLAIM

[21] Appl. No.: 887,449

The ornamental design for an electronic imager for biological samples, as shown and described.

[22] Filed: May 21, 1992

DESCRIPTION

[52] U.S. Cl. D24/233; D24/232
[58] Field of Search 356/344, 387; D24/233, D24/158, 159, 160

FIG. 1 is a perspective view of an electronic imager for biological samples showing our new design;
FIG. 2 is a rear elevational view thereof;
FIG. 3 is a top plan view thereof;
FIG. 4 is a bottom plan view thereof;
FIG. 5 is a left side elevational view thereof;
FIG. 6 is a front elevational view thereof; and,
FIG. 7 is a right side elevational view thereof.
